CLAIM

The ornamental design for a broiling grill, substantially as shown.

DESCRIPTION

FIG. 1 is a top plan view of a broiling grill, showing my new design;

FIG. 2 is a left side elevational view thereof;

FIG. 3 is a front elevational view thereof (the rear elevational view being the same);

FIG. 4 is a right side elevational view thereof;

FIG. 5 is a bottom view thereof;

FIG. 6 is a longitudinal sectional view taken along lines 6—6 of FIG. 1; and

FIG. 7 is a transverse sectional view taken along lines 7—7 of FIG. 1.
